CLAIM

The ornamental design for a cable guide device for guiding cables over multiple paths, as shown and described.

DESCRIPTION

FIG. 1 is a perspective view of the front face of a cable guide device for guiding cables over multiple paths of the present design to which cable captive elements (not shown) can be attached to space cables from the front surface;

FIG. 2 is a front plan view thereof showing mounting recesses for cable capture elements along the bottom and side edges;

FIG. 3 is a rear plan view thereof;

FIG. 4 is a top elevational view thereof;

FIG. 5 is a bottom elevational view thereof; and,

FIG. 6 is a left side elevational view thereof, the right side being a mirror image thereof.
